UNITED STATES PATENT OFFICE.

EMANUEL AUFIERO, OF BROOKLYN, NEW YORK.

DESIGN FOR A CASING AND BRACKET FOR DIAPHRAGM-ACTUATED SIGNALS.

41,791.

Specification for Design.

Patented Sept. 19, 1911.

Application filed April 22, 1911. Serial No. 622,823. Term of patent 7 years.

To all whom it may concern:

Be it known that I, EMANUEL AUFIERO, a citizen of the United States, residing at Brooklyn, in the county of Kings and State of New York, have invented a new, original, and ornamental Design for a Casing and Bracket for a Diaphragm-Actuated Signal, of which the following is a specification, reference being had to the accompanying drawing, forming part thereof.

The figures of the drawing show the design of the article.

Figure 1 is a side view. Fig. 2 is a rear view showing position and shape of bracket.

11 represents an enlarged forward portion of the casing, cylindrical as seen in Fig. 2, and comparatively shallow as seen in Fig. 1.

12 represents the intermediate portion of the casing, located at the rear of the portion 11, and cylindrical as indicated in Fig. 2.

13 represents the rearmost portion of the casing, cylindrical as indicated in Fig. 2, and very slightly smaller in diameter than portion 12 (as clearly seen in Fig. 1).

14 is the rounded rear face of the casing.

15 is the slight shoulder separating the intermediate cylindrical portion 12 from the reduced rear portion 13. And 16 represents

an ornamental beading located at the point where the intermediate cylindrical portion 12 unites with the flat rear face of portion 11 (as clearly seen in Fig. 1). The shoulder 15 is located nearer the rear face 14 than it is to the larger forward portion 11.

At the front of portion 11 is a large and bold ornamental portion 17, whose contour comprises the double curve (which may be described as a flattened S) arranged somewhat diagonally with respect to the axis of the entire design.

18 represents the bracket attached to the rear face of the portion 11, so as to be offset therefrom as seen in Fig. 1. This bracket comprises an elbow 19, the upper Y-shaped member 20, and the horizontal member 21, as seen in Fig. 2. The outer end of the horizontal arm 21, is provided with the enlargement 22.

I claim:

The ornamental design for a casing and bracket for a diaphragm actuated signal, as shown and described.

EMANUEL AUFIERO.
